CONTROL MEANS FOR SOUND RECORDING AND REPRODUCING MACHINES

Edgar L. Steed, Woodside, Long Island, N. Y., assignor, by mesne assignments, to Amertype Recordgraph Corporation, Elizabeth, N. J., a corporation of Delaware

Application May 2, 1941, Serial No. 391,533

13 Claims. (Cl. 274—11)

The device of the present application pertains to sound recording and reproducing and more particularly relates to a device in which the record medium consists of a strip of film with which may be associated a sound recording head and a sound reproducing or pick-up head.

The present application is a continuation in part of my application Ser. No. 327,582, filed April 3, 1940.

In devices of this character heretofore proposed, it has been necessary to provide a number of manipulative devices in order to adjust the mechanism to perform various functions.

The present application has for its main object the provision of a single manipulative means whereby a great many functions are performed. This single manipulative means in the present disclosure takes the form of a shaft having a knob extending to the outside of the casing, which knob may position the shaft in four different positions (1) record; (2) neutral; (3) reproduce or pick-up; and (4) thread. The shaft is provided with a number of devices principally in the form of cams by which the various elements are suitably positioned to perform the desired functions by merely setting the pointer of knob to the appropriate designation on an index formed on the casing.

The manner in which the single manipulative means controls the various elements of the device will be better understood from the following detailed description and claims when taken in connection with the accompanying drawings in which:

Figure 1 is a more or less diagrammatic perspective view showing the essential elements of the device; and

Figure 2 is a wiring diagram.

Referring to Figure 1, the record medium 2, in the form of a film, is fed through the machine in any well known manner and for purposes of illustration a sprocket 3 is provided for advancing the film. A pressure roller 4 applies suitable pressure to the film to thereby hold it firmly against the surface of the sprocket. In the conventional showing of Fig. 1, a backing plate 5 is situated beneath the film to form a firm surface for recording and reproducing purposes.

A recording head 6 has a rearwardly extending support 8 carried by arms 9 projecting forwardly from a sleeve 10. The arms 9 carry pivots at their ends which pivots engage the tone arm 8 whereby it may have vertical movement to enable the recording stylus 12 to be moved into

contact with the film or to be disengaged therefrom.

The pick-up head 14 is provided with a stylus 16 and in the position shown in Figure 1 (which is the recording position) said pick-up stylus 16 is shown disengaged from the film. To permit movement of the pick-up head relative to the recording head, an arm 15 secured to the pick-up head projects rearwardly therefrom and is pivoted at 16a to the support 8 of the recording head. The pivot 16a, however, is in the form of a bracket having a horizontally extending pin 17 which enters an aperture in the support 8 thereby providing for vertical movement of the pick-up head 14 as well as a slight lateral movement.

The position of the recording and pick-up heads is controlled by a single manipulative member which includes a shaft 18 the right hand end of which extends beyond the casing 19 and is provided with a knob 20 and a pointer 21. The casing is provided with notations by which the angular positions of the shaft 18 and knob 20 are indicated. The shaft is provided with a number of elements by which the various parts of the device are controlled.

Beginning at the right hand end of the shaft, there is a cam 22 which controls the position of the pressure roller 4. The next cam 24 to the left, controls the pick-up head 14. Cam 26 next to the left controls the recording head. Adjacent to cam 26 is a pinion 28 for controlling certain switches hereinafter more specifically described. The cam 30 controls the locking disc whose function will be described later. The cam 32 controls an indexing disc which will also be later more fully described.

With the pointer 21 of the knob 20 at the "record" position shown in Figure 1, the cam 22 is ineffective and the roller 4 holds the film in contact with the roller 3 through action of the spring 33 connected to bell crank 34, the arm 35 of which supports the roller. The cam 24 has its longest radius presented to a lever 36 pivoted at 37 and having a bent portion 38 which engages under the arm 15 thereby holding the pick-up head 14 in ineffective position in respect to the film. A wedge 37a is interposed between the cam 24 and the lever 36, in the figure 1 position, which wedge and its function will later be described. Cam 26, on the other hand, presents its shortest radius to a lever 40 pivoted at 41 with its bent over portion 42 clearing the underside of the tone arm 8. The lever 40 is urged to this position by a spring 43 and the recording head drops by its own weight into contact with

the film when the cam 26 permits the spring 43 to act.

Movement of the knob 20 through 180° in an anti-clockwise direction to "reproduce" position, causes the cam 22 to be rotated a like angular amount but the cam is so shaped that it has no effect on pressure roller 4, which continues to press the film 2 against feed roller 3. The cam 24, however, now presents its shortest radius to the lever 36 and the spring 44 then acts to rock the lever 36 about the pivot 37 so that its bent over portion 38 permits the pick-up head 14 to be lowered under its own weight to thereby permit its stylus 16 to engage the film. At the same time the cam 26 presents its longest radius to the lever 40 to raise the recording stylus 12 out of contact with the film.

Since it is contemplated that the present device may be used as a dictating machine, suitable means are provided whereby the recording stylus may be vibrated under control of sound impulses. In Figure 2 a microphone 46 is diagrammatically indicated as the source of such impulses.

The recording stylus is vibrated electrically and means are provided under control of the knob 20 by which suitable electrical connections are made between the microphone and stylus 16 when the knob 20 is in "record" position. These connections are brought about through the pinion 28 secured to the shaft 18 and which pinion is in engagement with a gear 48 of suitable size, the ratio in the present instance, for purposes of illustration, being approximately one to two. The gear 48 carries a pin 49 engaging an elongated slot in an arm 50 secured to switch shaft 51.

The shaft 51 is supported in a base member 52 which member also carries two multi-pole switches. The rotor of each switch is secured to the shaft 51 to rotate therewith. The rotor of the left hand switch includes an insulated disc 53 and conducting segments 55 and 56. The arc of movement of the shaft 51 is such that the conducting segment 55 is in constant engagement with terminal 60. This segment, however, is provided with a radial arm 61 which may engage terminal 62 when the switch is in the position shown in the drawings and thereby establish an electric connection between said terminal and the terminal 60. Similarly the segment 56 has a radial arm 63 which connects terminal 64 with terminal 65 when the switch is in the position shown. The terminals 60 and 65 are stationary and from them conductors lead to various instrumentalities which will be described in due course.

The rotor of the right hand switch includes an insulated disc 54, and conducting segments 57 and 58.

For convenience in referring to the conducting segments 55, 56, 57 and 58, these segments are also designated respectively by the Roman numerals I, II, III and IV. These designations will also be found convenient in using the tabulation near the end of the specification.

With the knob 20 in "record" position shown in Figure 1, terminals 60 and 62 are connected, likewise terminals 64 and 65; that is segments I and II are active. Under these conditions, referring to Figure 2, current is supplied from the secondary winding 66 of the output from the amplifier 66a. From 66 current passes through 61 to terminal 60 thence along segments 55 (I) to terminal 62, along conductor 68 to the recording stylus vibrating means 69, thence along con-

ductors 70 and 71 back to the secondary winding 66.

Segment 56 (II) by bridging terminals 64 and 65, connects the source of the sound i. e. the microphone 46, to the input circuit of an amplifier shown diagrammatically at 72a Figure 2. In the right hand switch the radial arm 74 of the segment 58 bridges contacts 75 and 76 to cause a pilot light to be displayed. The source of current supply for the pilot lights (of which there are three) is indicated at A—B. The current passes from A, for instance, along wire 77 to terminal 76, thence along segment 58 (IV) to terminal 75 and through conductors 78 and 79 and 80 to pilot light 81 which may be a red light. With the knob 20 in "record" position, the segment 57 (III) of the right hand switch does not function.

If the knob 20 is moved from "record" position to "reproduce" position, the cams 24 and 26 function as already described to reverse the position of the recording and pick-up heads, but due to the one to two ratio in the gearing between 28 and 48, the segments I, II, III, and IV rotate through 90° only. Under these conditions the segment 55 (I) would have caused the contact to be broken at the terminal 62 and said segment will then perform no further function. The segment 56 (II), however, will have moved its radial arm 63 into contact with terminal 82 to thereby connect the pick-up head 14 with the amplifier through the medium of conductors 83 and 84, Figure 2. At the same time, the segment 58 (IV) of the right hand switch will have moved the radial arm 74 into contact with terminal 86 to establish a circuit through the pilot light 86 which for purposes of illustration, is shown as green. A current passes from A through conductor 77 to terminal 76, thence through segment 58, radial arm 74 to terminal 86. From terminal 86 the current passes through conductor 89 to pilot 88. From the pilot it passes through conductor 89 to pilot 88. From the pilot it passes through conductor 90 back to B terminal of the supply circuit. The segment 57 (III) of the right hand switch causes its radial arm 92 to contact terminal 93 thereby connecting the loud speaker 94 with the coil 66, said connection being by way of conductors 95, 96, 71 and 97 to stationary terminal 98 of the right hand switch.

Reference has heretofore been made to the cams 30 and 32 on the shaft 18 and in order to understand their function, it will first be necessary to describe certain parts which are associated with, and to some extent control, the lateral movement of the recording and pick-up heads with reference to the film.

Referring to Figure 1, the sleeve 10 carrying the arms 9, which directly support the recording head, is internally threaded, which threads engage corresponding threads 11 on a shaft 100, the right hand end of which extends through the casing 19 and is provided with a knob 102 whereby the shaft 100 may be rotated manually. Means are provided, however, whereby the recording and pick-up heads may automatically be moved step by step transversely of the film and to do this the shaft 100 is rotated step by step under control of the film itself.

In the present construction the film 2 is preferably a continuous film, that is to say, its ends are joined together and the film is fed through the machine in successive cycles. The film 2 is preferably formed of material which is non-

electrically conducting. A portion of the film, however, is provided with an electrically conducting element 103, which extends on both surfaces of the film 2 and at suitable times bridges contact between upper and lower contact rollers 104 thereby closing a circuit through a relay 106. The armature of this relay forms one arm of a switch 105 which when the relay is energized contacts a stationary terminal 108 which closes a circuit through solenoid 110. 10 The circuit established by the contact 103 may be traced as follows: From the terminal C, current passes along conductor 111 to junction 111^a, through conductor 112 to the under contact roller 104, thence through the contact 103 to the upper roller 104 and through conductor 113 to relay 106. From the relay it passes by way of conductor 114 to junction 115, thence through conductor 116 to junction 117. From junction 117 the current passes along conductor 117^a and through conductors 117 and several switches indicated by the reference letters Z², Z³, Z⁴, and Z⁵, all of which are closed when the knob 20 is in either "record" or in "reproduce" position. These several switches will later be described and their functions pointed out. For the present, it is sufficient to state that the current finally passes along conductor 117^b, to junction 117^c, and through switch Z¹, which is closed, to the terminal D.

Relay 106 being energized, closes switch 105. As soon as the switch 105 is closed, current passes directly from terminal C to solenoid 110 and from the solenoid through the switch 105 back to terminal D. Energization of solenoid 110 causes a pawl 118 to rock about its pivot 119 to thereby disengage its tooth 120 from index disc 122. This index disc and a locking disc 124 are both secured to shaft 100. The locking disc is normally held in locked position by a pawl 125 40 under control of spring 125^a. The index disc and locking discs are in the form of ratchets having their teeth facing in the opposite direction. Thus when both the pawl 118 and the pawl 125 are in locking position, shown in Figure 1, the shaft 100 cannot be rotated in either direction. If the pawl 118 were moved to inoperative position, however, the shaft 100 could be rotated in a clockwise direction since the pawl 125 would permit this since this pawl would merely be moved up and down as the locking disc 124 were turned.

The lifting of the pawl 118 under control of the film energizes a motor 126 which rotates shaft 100 which through the screw threads 55 thereon engaging the interior threads of the sleeve 10 causes lateral movement of the recording and pick-up heads. The speed of rotation of the motor is reduced through a gear box 127 which latter through a friction clutch 128 drives disc 129 secured to the shaft 100. The lifting of the right hand end of the pawl 118 causes contact to be made at terminal 130 of switch 131 to thereby close the motor circuit. The instant the motor starts to turn, the high part 60 of a tooth of the wheel 122 prevents the pawl 118 from dropping under stress of its spring 132 thereby holding the motor circuit closed. The circuit for the motor may be traced as follows: From terminal C, the current passes through conductor 111 to junction 134, through 135 to the motor 126; from the motor it passes through conductor 136 to switch arm 131 thence, through the pawl 118 to its pivotal point 119, that portion of the pawl being electrically conducting. 70

From the pivot point 119, the current flows through conductor 137, to the closed switch Z⁵, thence along conductor 137^a to junction 137^b. From 137^b it passes along conductor 116 to junction 117. When the several switches Z⁵, Z⁴, Z³ and Z² are closed the result is the same as though junction 117 were directly connected with junction 117^c since conductor 117^b and the several switches and the conductors therebetween, indirectly connect junctions 117 and 117^c.

From the mechanism just described, it is obvious that every time the film makes a complete cycle and the conducting portion 103 bridges the contacts 104, the motor 126 is energized and causes the shaft 100 to be turned in the direction of the arrow, Figure 1. The amount of turning, however, is controlled by the index disc 122 in cooperation with the pawl 118 and tooth 120. The stoppage of the motor is brought about by the tooth 120 dropping into the next adjacent notch of the disc 122 thereby breaking the motor circuit at the switch 131. The pawl arrests the disc 122 after it has made a definite degree of rotation and although the motor does not instantly stop, such overrunning is taken care of by means of the friction clutch 128.

From the foregoing, the function of the cams 30 and 32 will be understood. With the knob 20 in the "record" position, pawls 118 and 125 are 30 effective to lock the shaft 100 against any manual rotation. The film contact 103, however, may permit the motor 126 to give to shaft 100 a step by step rotation. The cams 30 and 32 do not interfere with the temporary disengagement of pawls 118 and 125 from their respective ratchet wheels during such automatic control of the shaft 100. To this end the pawl 125 has attached to its left hand end, a link 138 having a bent portion 140 and a cam engaging part 141. When the locking disc 124 is rotated by the motor, under automatic control of the film, the pawl 125 moves up and down, but the cam engaging part 141 of the link 138 merely moves away from or close to the face of the cam 30.

A similar construction permits the pawl 118 to be moved to cause its tooth 120 to be disengaged from the index disc 122 but only in "neutral" position of knob 20. This pawl has a link 142 pivoted near its left hand end and the lower end of this link is provided with a roller 143 with which the cam 32 may engage to lower the left hand arm of the pawl 118 to thereby lift its tooth 120 out of engagement with the index disc. The cam 32 has most of its surface concentric with the shaft 100, but is elongated along one radius, as shown. When the knob 20 is moved from the position shown in Figure 1, to "neutral" position the cam 32 renders pawl 118 ineffective. Cam 30 also renders pawl 125 to engage the teeth of locking disc 124 so that in "neutral" position, both heads may be positioned by the knob 102.

When in "record" position both pawls 118 and 125 are active. In "reproduce" position, the pawl 125 is rendered ineffective but the pawl 118 engages the index disc 122, except at those times when the solenoid 110 is energized.

In order to appreciate the reasons for this sequence of action, it is to be borne in mind that during reproducing the stylus 16 is engaged with film while the stylus 12 is disengaged. In order that the pick-up stylus may transverse the film step by step, the pawl 118 must function in the manner previously described. The pawl 125, however, whose primary function is to prevent manual traverse of the sound heads, is rendered

ineffective so that the pick-up stylus 16 may be moved to different positions transversely of the film by manual rotation of the knob 102, since the pick-up stylus may be of a material which will not injure the film even though the stylus moves across it while in engagement with it. The pick-up head is also lighter than the recording head.

On the other hand, the recording stylus 12, 10 may be of harder material than the pick-up stylus in order to form a sound track in the film but due primarily to its greater weight it is highly undesirable that this stylus should be permitted to be moved across the film when the recording stylus is in engagement therewith. 15 Therefore, in "record" position, the pawl 125 is operative to prevent any manual traversing of the recording stylus, but as previously described, the recording stylus may be moved step by step under control of the index disc 122 without interference from the pawl 125.

When the knob 20 is moved to "neutral" position the cam 22 still remains inactive and therefore roller 4 holds the film in contact with the sprocket 3. The "pick-up" or reproducing head 14, is up because the cam 24 is so shaped that it holds the head up except in "reproduce" position, or as its action is modified by the wedge 37^a. The recording head is also up, as the cam 26 is properly shaped to accomplish this result.

The segment I, is in "off" position with contact 61 disengaged from 62.

Segments II and III are both "on" in order that the system may be used for a public address. To accomplish this a contact 64^a is electrically connected to 64 and contact 93^a is electrically connected to 93. Segment II has its arm 63 in contact with 64^a with knob 20 at "neutral" and segment III has its arm 92 in contact with 93^a, at this time. Therefore the microphone will be connected to the input of the amplifier and the loud speaker to the output.

Segment IV connects arm 74 with contact 144 to cause pilot light 145 to show a white light. A circuit to this light includes conductors 17, 146, 45 147 and 90.

The fourth or "thread" position of the knob 20 is used when it is desired to introduce a film into the machine. For this purpose it is necessary to lift the pressure roller 4 from off of the film and the cam 22 has a projecting portion 148 which engages the end of rod 149 supported at 150 and 151 to move said rod in the direction of the arrow to thereby rock the bell crank 34. This bell crank is eccentrically mounted so that the roller 4 moves in a path away from the sprocket 3.

In the "thread" position the "pick-up" head and the recording head are both up, and segment I is in such a position that no current is supplied to the recorder.

Segments II and III controlling the electrical connections to the "pick-up" and loud speaker are on, and may serve as an audible means for testing whether there is any looseness of parts of the mechanism. The green pilot light is "on" and the connection to the microphone is "off."

In the early part of the specification, reference was made to switches Z¹ to Z⁵ inclusive. Switch Z¹ is in the main line and when this switch is open no current flows to any of the instrumentalities of the machine. Switches Z² to Z⁵ inclusive are provided more or less as safety devices.

Switch Z² is operated by a pin 154 and extends to the right from the right hand arm 9 supporting the recording head. When the recording

head has transversed the film and moves beyond the last track to be recorded, the pin 154 opens the switch Z² and no current is supplied to the motor 157, which drives the film.

The shaft 156 upon which the sprocket 3 is mounted is a continuation of the motor shaft. Current to the motor 157 passes from the terminal C to junction 158 and thence along wire 159 to a motor terminal 160. After passing through the motor, it emerges at 161 and passes along wire 162 to junction 163, thence to junction 117. From 117 to passes along conductor 117^a and through switches Z⁴ to conductor 163, to switch Z³; thence through switch Z², through conductor 117^b to terminal 117^c and through switch Z¹, to terminal D, Z¹ being closed at this time.

When the film is being threaded through the machine it is not usually in taut position and when this occurs the switch Z³ opens, since it is normally held closed under taut condition of the film. Therefore, even though the switch Z¹ has not been manually opened, the current to the motor 157 is broken at Z³ and the motor automatically stops.

25 The switch Z⁴ is also open in "thread" position under action of a pin 164, carried by the disc 48. In Fig. 1 the disc 48 is shown in the "record" position. With the knob 20 in the "thread" position, the disc moves through an angle of 157^{1/2} degrees and at that time the pin 164 is so positioned that it opens the switch Z⁴ and even though the switch Z³ happens to be closed, and no current is supplied to the motor 157.

It will thus be seen that Z³ and Z⁴, each control the current to the motor 157 and while Z³ is opened by reason of the film being slack during the threading, the main purpose of the switch Z³ is to stop the motor in case the film should break.

30 The switch Z⁵ is also opened by the pin 164 when the knob 20 is in neutral position. This is brought about by the fact that from "record" position to "neutral" position, the knob 20 is moved through 90°, but due to the one-to-two ratio between the disc 28 and the disk 48, the latter moves only 45 degrees. At this time, the switch Z⁵ is open and thereby opens the circuit to the carriage motor 126. It does not, however, effect the circuit to the motor 157.

35 Switches Z², Z³ and Z⁴ must all be closed in order that the motor 157 be supplied with current. It is also necessary that these three switches be closed and switch Z⁵ likewise closed, in order to supply current to the carriage motor 126.

40 It has been previously stated that the cam 24 normally controls the positions of the reproducing head and reference has been made to a wedge 37^a situated between the surface of the cam 24 and the lever 36. The wedge 37^a is shown in its engaged position in Fig. 1 in which position the cam 24 holds the "pick-up" head 14 out of contact with the film in "record" position and into contact with the film in "reproduce" position. It may sometimes be desirable to monitor while recording and for that purpose, it is desirable to have the recording stylus and the reproducing stylus both in engagement with the film and to provide means whereby the record may be listened to. The wedge 37^a provides a portion of such means. When the wedge is withdrawn from the position shown in Fig. 1, the reproducing stylus is permitted to engage the film.

45 Movement of the wedge is controlled by an arm 166 to which the wedge 37^a is pivoted. The arm 166 is carried by a shaft 168 which extends

through the panel board 19 and at its end carries a handle 169 by which the shaft may be rocked from one position to another. The shaft is yieldingly held in either position by a spring detent 170 engaging notches 171 in a disc 172 secured to the shaft 168.

In order that the vibration of the reproducing stylus may be heard, the conductor 83 Fig. 2 is tapped and two wires 174 and 175 extend to a jack indicated generally by the reference character 176. A plug to which ear telephones may be attached is inserted in the jack and the vibrations of the "pick-up" may be heard through these ear telephones. When the plug has been withdrawn the current through the "pick-up" head passes along conductor 83 and 174 to contact point 178 back through wire 175 to contact point 82 as is necessary in the normal operation of the device.

In order that the positions of the various parts may be readily followed a tabulation is hereby appended.

	Record (1) 0°	Neutral (2) 90°	Reproduce (3) 180°	Thread (4)
Pressure roller	Down	Down	Down	Up.
Pick-up	Normally up manually set up or down.	Up. Up.	Down	Up. Up.
Recording head	Down	Up.	Up.	Up.
Segment I: Recorder	On	Off	Off	Off
Segment II: Pick-up	Off	On	On	On
Segment III: Loud speaker	Off	On	On	On
Segment IV:				
Red pilot	On	Off	Off	Off
White pilot	Off	On	Off	Off
Green pilot	Off	Off	On	On
Microphone	On	On	Off	Off

What I claim is:

1. In a sound recording and reproducing device, a record medium, a recording head, a pick-up head, both said heads movable laterally in relation to said record medium, means for locking both said heads from lateral movement in either direction, a single manipulative member having a recording position and a neutral position, and means controlled thereby and associated with said locking means for rendering said locking means effective when said member is in recording position and for releasing said locking means when said member is in neutral position.

2. In a sound recording and reproducing device, a record medium, a recording head, a pick-up head, both said heads movable laterally in relation to said record medium, means for locking both said heads from lateral movement in either direction, a manipulative member having a recording position and a reproducing position, and means controlled thereby and associated with said locking means to render said locking means effective when said member is in recording position and to render said locking means ineffective to prevent lateral movement in one direction only when said member is in reproducing position.

3. In a sound recording and reproducing device, a record medium, a recording head, a pick-up head, both said heads movable laterally in relation to said record medium, a lock for preventing lateral movement of said heads in one direction, a second lock for preventing lateral movement in the other direction, and means for releasing both locks to permit free lateral movement of both heads.

4. In a sound recording and reproducing device, a record medium, a recording head, a pick-

up head, both said heads movable laterally in relation to said record medium, a lock for preventing lateral movement of said heads in one direction, a second lock for preventing lateral movement in the other direction, a single manipulative member having a recording position and a neutral position, and means controlled thereby and associated with said locks for rendering both locks effective or both ineffective, according to the position of said member.

5. In a sound recording and reproducing device, a record medium, a recording head, a pick-up head, both said heads movable laterally in relation to said record medium, a lock for preventing lateral movement of said heads in one direction, a second lock for preventing lateral movement in the other direction, a single manipulative member having a recording position and a neutral position, and means controlled thereby and associated with said locks for rendering both locks effective when said member is in recording position and for rendering both locks ineffective when said member is in neutral position.

6. In a sound recording and reproducing device, a record medium, a recording head, a pick-up head, both said heads movable laterally in relation to said record medium, a lock for preventing lateral movement of both said heads in one direction, a second lock for preventing lateral movement in the other direction, a manipulative member having a recording position and a reproducing position, and means controlled thereby when in reproducing position to release one of said locks while maintaining the effectiveness of the other lock.

7. In a sound recording and reproducing device, a record medium, a recording head, a pick-up head, both said heads movable laterally in relation to said record medium, means for locking both said heads against lateral movement in either direction, a manipulative member having a recording position and a threading position, and means controlled thereby to render said locking means effective when said member is in recording position and to render one only of said locking means ineffective when said member is in threading position.

8. In a sound recording and reproducing device, a recording stylus, a pick-up stylus, means for vibrating said recording stylus in accordance with sound impulses, a record medium, a single manipulative member, a cam shaft rotatable thereby, a cam on said shaft and connections from said cam to said pick-up stylus to render the same ineffective to engage the record medium, a second cam on said shaft and connections from said cam to said recording stylus to engage the same with the record medium, a pinion on said shaft, a rotary switch controlled by said pinion, said switch operating to connect said source of sound impulses with said recording stylus vibrating means.

9. In a sound recording and reproducing device, a record medium, a recording stylus and a reproducing stylus each adapted to engage said medium, means for vibrating said recording stylus in accordance with sound impulses, a single manipulative member, a cam shaft rotatable thereby, a cam on said shaft and connections for said cam to said reproducing stylus to render the same ineffective to engage the record medium, a second member on said shaft and connections from said cam to said recording stylus to engage the same with the record medium when said pick-up stylus cam is positioned to render

said pick-up stylus ineffective, a pinion on said shaft, a rotary switch controlled by said pinion, said switch operating to render said stylus vibrating means effective.

10. A sound reproducing device, a record medium, a pick-up stylus adapted to engage said medium, a loud speaker associated with said pick-up stylus, a single manipulative member, a shaft rotatable thereby, a cam on said shaft connections from said cam to said pick-up stylus to render the same effective to engage the record medium, a pinion on said shaft, a switch controlled by said pinion, said switch acting to engage said loud speaker with the pick-up stylus when said cam renders said pick-up stylus operative to engage the record medium.

11. In a sound recording and reproducing device, a record medium, a recording stylus, a pick-up stylus, means for vibrating said recording stylus, a loud speaker associated with said pick-up stylus, a single manipulative member having a recording position and a reproducing position, a shaft rotatable by said member, cams on said shaft, a pinion on said shaft, a gear engaging said pinion, rotatable switches movable with said gear, connections from said cams to said recording stylus and to said pick-up stylus, and connections from said switches to said recording stylus vibrating means and to said loud speaker.

12. In a sound reproducing device, a record medium, a pick-up stylus support movable to place the stylus into and out of engagement with said medium, a lever connected to said stylus support, a cam cooperating with said lever and having a position in which it moves and holds said stylus disengaged from the medium and a position in which said cam permits said stylus to drop by gravity into engagement with the medium, and means to permit said stylus to drop into engagement with the medium even though the cam is in a position normally to prevent engagement.

13. In a sound reproducing device, a record medium, a pick-up stylus support movable to place the stylus into and out of engagement with said medium, a lever connected to said stylus support, a cam cooperating with said lever and having a position in which it moves and holds said stylus disengaged from the medium and a position in which said cam permits said stylus to drop by gravity into engagement with the medium, and means to permit said stylus to drop into engagement with the medium even though the cam is in a position normally to prevent engagement, said latter means including a wedge movable into a position between said lever and the active surface of said cam.
